Assignor to

Des. 1121

The Lowell Manufacturing Company
Letters Patent No. 4421. Dated July 5, 1856;

The design is referred to in these Letters Patent and making part of the same.

Statement, where it may concern:

It is known that I, Elmer J. Ney, of Lowell in the County of Middlesex, and State of Massachusetts, have originated and designed a new pattern for carpets and other fabrics, of which, the following is a full, clear and exact description, reference being had to the accompanying drawings, . . . making a part of this specification.

The center A, consists of a Rosette 1, resting on a ground of web work 2, surrounded by a garland of leaves and flowers 3, resting on a scalloped circle 4, composed of a narrow band outside, and dots decreasing in size as the run inward.

The center B, is composed of a new combination of gothic work bordered with sprigs.

The sides C, consists of small groups of leaves, resting on an indented ground 6.

The colors employed for the different portions of the design, may be varied to suit the taste and wishes of the manufacturer.

Claim.

What I claim as my invention, and desire to secure by Letters Patent, is the design or pattern for carpets herein set forth.
